INVENTOR

Nicholas Zuck

BY
Harold E. Stonebraker,
his ATTORNEY

UNITED STATES PATENT OFFICE.

NICHOLAS ZUCK, OF ROCHESTER, NEW YORK.

STAY MEMBER FOR COAT COLLARS.

Application filed March 28, 1921. Serial No. 456,369.

To all whom it may concern:

Be it known that I, NICHOLAS ZUCK, a citizen of the United States of America, residing at Rochester, in the county of Monroe and State of New York, have invented certain new and useful Improvements in Stay Members for Coat Collars, of which the following is a specification.

My invention relates to a stay member 10 for coat collars, and has for its object to provide a device of this character which can be economically manufactured, and possesses the desired requisites for imparting to a coat collar the necessary smoothness, stiffness, and tendency against breaking or creasing.

The invention will be more clear from the following description in conjunction with the accompanying drawings, the novel 20 features being pointed out in the claims at the end of the description.

In the drawings:

Figure 1 is a rear elevation of a coat, showing the manner of application of the 25 invention.

Figure 2 is a sectional view on line 2—2 of Figure 1, and

Figure 3 is a view in elevation of the stay member, showing its laminations partially 30 pulled apart.

The construction is intended to be used to stiffen that portion of a coat at the upper part of the back, which lies against the collar of the person, the object being to prevent such collar portion of the coat from 35 breaking or creasing at the base thereof, and thereby destroying the appearance of the coat.

The device includes a layer A of stiffening material, such as hair-cloth, and a layer 40 B of padding material, such as felt. The

hair-cloth which I employ is preferably of a finely woven character, such as known in the trade as "hymo" and consisting of cotton or wool woven with mohair or Chinese hair. The hair-cloth is treated, to impart stiffness thereto, by immersing it in a solution of cementitious or waterproofing substance which also serves to retain the felt layer against the hair-cloth fabric, the parts 45 being preferably secured together in the first instance by mechanical pressure.

The stay member is cut according to a pattern, conforming generally to the shape shown in Figure 3, and is then secured to the 50 coat as indicated in Figure 2, and the dotted lines of Figure 1. The felt gives the necessary body and padding to the collar portion, while the processed hair-cloth fabric imparts the necessary stiffness and resistance 55 to breaking.

The important feature of the invention lies in the application to the collar portion of a coat of a stiffening or stay member 60 consisting of laminations of a stiffening fabric and a padding fabric, the stiffening fabric being treated with a cementitious stiffening solution which also acts to retain the laminations together.

I claim:

A stay member for coat collars having its opposite lengthwise edges curved and substantially parallel, whereby the structure conforms to and can be easily attached to a coat collar without cutting, and including 65 a layer of felt and a layer of haircloth impregnated with a cementitious substance, the haircloth functioning both to stiffen the structure and to secure the felt thereto.

In witness whereof, I hereunto sign my 70 name.

NICHOLAS ZUCK.
